(57) **CLAIM**

The ornamental design for a combination speaker/wireless phone charger, as shown and described.

DESCRIPTION

FIG. 1 is a top isometric view of a combination speaker/wireless phone charger showing our new design.

FIG. 2 is a bottom isometric view thereof.

FIG. 3 is a front side elevation view thereof.

FIG. 4 is a back side elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a top isometric view of an alternative embodiment of a combination speaker/wireless phone charger showing our new design.

FIG. 10 is a bottom isometric view thereof.

FIG. 11 is a front side elevation view thereof.

FIG. 12 is a back side elevation view thereof.

FIG. 13 is a left side elevation view thereof.

FIG. 14 is a right side elevation view thereof.

FIG. 15 is a top plan view thereof; and,

FIG. 16 is a bottom plan view thereof.

(Continued)

The broken lines are for illustrative purposes only and form no part of the claimed design.

1 Claim, 10 Drawing Sheets
